UNITED STATES PATENT OFFICE.

HENRY C. WEEDEN, OF QUINCY, MASSACHUSETTS.

DESIGN FOR A CASING FOR STOP-COCKS.

SPECIFICATION forming part of Design No. 29,473, dated October 11, 1898.

Application filed December 3, 1897. Serial No. 660,710. Term of patent 7 years.

To all whom it may concern:

Be it known that I, HENRY C. WEEDEN, a citizen of the United States, residing at Quincy, in the county of Norfolk and State 5 of Massachusetts, have invented and produced a certain new and useful Design for a Casing for a Stop-Cock, of which the following is a specification.

In the accompanying drawings, Figure 1 is o a side elevation of a casing for a stop-cock made in accordance with my design. Fig. 2 is an end elevation, and Fig. 3 a top plan view, of the same.

My design comprises a central body portion 5 2, the side edges of which are substantially rectangular, as shown in Fig. 1, and which has the general form of a square when viewed as shown in Fig. 2. The square faces of this central body portion are slightly convexed o when viewed as in Fig. 3, and from each of them projects a cylindrical portion 3, con-

nected with the body portion 2 by shoulders 4, curving outwardly in all directions, as shown. The outer ends of the portion 3 are somewhat enlarged and formed with flat-sided edges 5. 25

The bottom edge of the body portion 2 is enlarged laterally and formed into a short cylindrical projection 6, and the top edge of the portion 2 is also formed into a short substantially cylindrical portion 7, which, however, is provided with laterally-projecting wings 8, as best shown in Fig. 3.

I claim—

The design for a casing for a stop-cock herein shown and described.

In testimony whereof I have hereunto subscribed my name this 1st day of December, A. D. 1897.

HENRY C. WEEDEN.
